UNITED STATES PATENT OFFICE.

JAMES LEE, OF NEW BRIGHTON, NEW YORK.

FOLDING GRAPHOSCOPE.

SPECIFICATION forming part of Letters Patent No. 252,321, dated January 17, 1882.

Application filed August 10, 1881. (No model.)

To all whom it may concern:

Be it known that I, JAMES LEE, of New Brighton, Richmond county, New York, have invented an Improvement in Graphoscopes, of 5 which the following is a full, clear, and exact description, reference being had to the accompanying drawings, forming part of this specification.

My invention relates to a graphoscope; and 10 it consists in the peculiar devices hereinafter particularly described, and more at length recited in the claims.

Figure 1 is a side elevation of a graphoscope apparatus embodying my invention. Fig. 2 is 15 a plan of the same. Fig. 3 is a rear end view of the same, the lens-piece on the front not being shown. Fig. 4 is a side elevation of the same on a reduced scale, and showing the parts in position for use; and Fig. 5 is a front view 20 on a similarly-reduced scale, showing the lens-piece and base-bar.

A is the base, upon which the working parts are mounted in three portions, extending longitudinally of said base, the central portion, a, 25 of which is hinged at the rearward end at a² to the standard B, and the portions a' on either side of the central portion, a, being made to slide longitudinally on said portion a by suitable means, such as the tongues and grooves 30 shown plainly in Fig. 3.

The standard B is preferably made in the form of a box, as shown, and being thus made, the portions a a' of the base-plate A, when they are adjusted in the closed position shown in 35 Fig. 1, constitute a hinged cover for said box. A bar, C, which constitutes the support for the lens-piece D, extends across the base from one to the other of the forward ends of the slides a', to each of which it is there hinged, as seen at c.

40 The lens-piece D carries the graphoscopic lens at d. Upon the central fixed portion, a, of the base, at the rearward end, is hinged the graphoscopic picture-holder E.

The lens-piece D is detachably seated on the 45 supporting-bar C, and this is accomplished by means of pins d² on its lower edge fitting into sockets c' in the upper face of said bar.

G G are leaf-springs, which are fastened at g to the upper face of the slides a', as shown, 50 and their free ends g' bear upon the extremities of the hinged supporting-bar C at each end thereof, as seen plainly in Fig. 2.

The upper face of the supporting-bar C is preferably rounded off to facilitate the operation of the parts. I thus produce a convenient 55 means of holding the bar C and the lens-piece which it supports in an upright position, the springs acting to prevent its falling backward upon the base, while by a slight pressure exerted upon the lens-piece the force of the springs 60 may be overcome and the bar C and lens-piece be folded backward upon the base, as seen in dotted lines in Fig. 1, where it will be held thus folded down by the pressure of the springs 65 upon the upturned side face of the bar.

Suitable devices for sustaining the base and its supported parts at a desirable incline or angle on the standard when using the instrument are provided, as seen in Fig. 4.

It is evident that by means of the devices 70 and their arrangement which I have described I constitute an instrument in which the lens-piece, which is in convenient reach of the user without getting the hand between the lens and the picture, may be drawn from or pushed toward the fixed picture-holder, the lens-piece being mounted on the slides a' and the picture-holder being fixed on the base a.

It is also evident that by means of the devices described the lens piece may be readily 80 unseated from the bar C on the slides at pleasure and packed within the standard or box B during transit of the instrument from place to place.

It is also evident that the devices I have 85 shown and described are applicable to either an instrument combining both stereoscope and graphoscope or to one constituting a stereoscope or graphoscope alone.

When a combined graphoscope and stereoscope is constructed embodying my invention the lens-piece D is arranged to carry the graphoscopic lens in the upper portion of said piece, as at d, and the stereoscopic lenses in the lower portion of said piece, as at d', and a stereoscopic picture-holder is rigidly secured on the fixed portion a of the base, about midway thereof, as at F, all plainly seen in Fig. 1.

I do not claim broadly a graphoscope in which the picture-holder is rigidly fixed on the base-plate and the lens-holder is movable; nor do I claim broadly a graphoscope in which the lens-holder is capable of being held erect by springs or of being folded down upon the base-

plate; nor do I claim broadly a lens-holder detachable from the base-plate; but I desire to claim only the devices shown and described by means of which the objects herein specified are attained.

5. What I claim as my invention, and desire to secure by Letters Patent, is—

1. In a graphoscope apparatus, the base A, composed of the central portion, a , and the side pieces, a' , the central portion being hinged to the standard B, and having fixed thereto the picture-holder, and the said side pieces being arranged to slide longitudinally on said central portion and carrying the lens-holder, and the entire base-plate thus constructed being adapted, when closed, to act as a cover for a box-like standard, as and for the purpose specified.

15. 2. In a graphoscope apparatus, the combina-

tion, with the slides a' , working on the central portion, a , of the base-plate, of the supporting-bar C, extending from one to the other of and hinged to the said slides and carrying the lens-holder D, together with the leaf-springs G, acting upon the extended ends of said bar, all substantially as and for the purpose specified.

20. 3. In a graphoscope apparatus having the hinged supporting-bar C, carried by the slides a , the lens-holder D, detachably seated on said supporting-bar by means of the pins d^2 and sockets c' , as and for the purpose specified.

25. Witness my hand August 8, 1881.

JAMES LEE.
